Patented Mar. 8, 1921.

UNITED STATES PATENT OFFICE.

DENNIS L. DRISCOLL, OF COALINGA, CALIFORNIA, ASSIGNOR OF ONE-HALF TO
BUNTING IRON WORKS, OF SAN FRANCISCO, CALIFORNIA, A CORPORATION
OF CALIFORNIA.

FISHING-TOOL AND SUPPORT.

1,371,078.

Specification of Letters Patent. Patented Mar. 8, 1921.

Application filed May 22, 1920. Serial No. 383,463.

To all whom it may concern:

Be it known that I, DENNIS L. DRISCOLL, a citizen of the United States, residing at Coalinga, in the county of Fresno and State 5 of California, have invented certain new and useful Improvements in Fishing-Tools and Supports, of which the following is a specification.

The present invention relates to that type 10 of implement commonly known to well drillers as a fishing tool, and the invention has for its principal object to provide a type of tool particularly adapted for the recovery of shouldered or collared implements, such 15 as a string of pipe or tubing from a well. A further object is to provide a simple form of mounting or support for my present invention whereby the same may be readily and rapidly positioned in the support for 20 lowering into a well for the recovery of the lost implements without loss of time, and one which is adapted to receive a plurality of tools constructed different from the present invention, but for the same purpose.

25 To comprehend the invention, reference is directed to the accompanying drawing, wherein—

Figure 1 is a vertical sectional view of the preferred embodiment of my invention, dis- 30 closing the holder and tool.

Fig. 2 is a transverse sectional view taken on line 2—2 of Fig. 1, viewed in the direction of the arrows.

In the drawings, referring particularly to 35 Fig. 1 the numeral 1 indicates a tubular steel shell preferably interiorly threaded at its upper and lower ends as at 2 and 3. The shell 1 at its lower end, immediately above the threads 3, is provided with an an- 40 nular inwardly projecting shoulder 4 having an inwardly beveled upwardly inclined guiding face 5 and a relatively flat trap ring supporting shoulder 6, the face of which is preferably disposed at right angles to the 45 body of the shell 1, and said face is disposed a distance below the upper threaded end 2 of said shell, as in Fig. 1 of the drawings.

50 Removably positioned within the upper open end of the shell 1, prior to the thread- 55 ing of the pipe 7 to the thread 2 for lower- 60 ing the shell into the well, is a trap ring 8 of the diameter slightly less than the in- 65 terior diameter of the shell 1. The trap

ring 8 is provided with a relatively flat edge 9 adjacent to its lower peripheral edge for 55 resting on the trap ring supporting shoulder 6, and the inner surface of said ring is upwardly and inwardly beveled as at 10, said bevel being preferably at substantially the same inclination as that of the bevel 5 to insure the guiding of the member over which the tool is lowered through the opening in the center of the ring 8.

The upper surface of the ring 8 carries an upstanding boss 11 the opposite faces of 65 which lie in spaced relation to the inner and outer wall surfaces of the ring, providing a liner seat 12 at the outer side of the boss and a trap dog seat 13 at the inner side. The boss 11 is vertically slotted for its full depth at a 70 plurality of points as at 14, and in its outer face is formed with an annular ring receiving groove 15 in which is adapted to be received or sprung a split ring 16. The ring 16 mounts a plurality of trap dogs 17, illus- 75 trated as four in number, which are arcuate in plan, and disposed to lie adjacent the inner surfaces of the boss 11 with their lower surfaces resting on the seat 13.

From the rear of each trap dog 17 extends 80 a tongue 18, one of said tongues extending through each of the slots 14, and their terminal ends are each provided with an opening through which the ring 16 extends. The trap dogs 17 when mounted, as in the 85 drawings, provide a substantial circular opening overlying the seat 13, and of a diameter smaller than the opening in said ring 8. The engaging surfaces of said trap dogs 17 are provided with cam faces 19, the upper edge of which terminates in a biting 90 edge 20.

To retain the trap ring 8 on its seat and preclude vertical movement of the same within the shell 1, and to permit the use of 95 trap rings or other members of various heights, a suitable tubular liner 21 is positioned within the shell 1, and the same is adapted to rest at its lower edge on the liner seat 12 of the ring 8, and at its upper edge 100 the same is engaged by the lower edge of the pipe or member threaded into the upper end of the shell 1.

The removability of the trap ring 8 with its associated dog 17 as a unit from the shell 105 1, enables other tools or members to be posi-

tioned within the shell, just so long as the auxiliary members are of a diameter to rest on the shoulder 6, and the provision of a removable liner 21 intermediate the lower end 5 of the pipe 7 and the shoulder 6 enables the employmnet of trap rings or other bases of various heights.

By my improved construction it will be apparent that the trap dogs will upwardly 10 pivot and slide freely over the walls of any member of a diameter capable of reception within the central opening of the trap ring, on the lowering of the device thereover, and said trap dogs will serve as cam members 15 and engage the wall of the member received therebetween on the upward movement of the device. If such received device is of a diameter smaller than that of the opening formed by the trap dogs when the same are 20 in their horizontal position, and is provided with a flange or collar of a diameter greater than the diameter of the opening formed by said trap dogs in said position, said dogs will, on the rising of the shoulder above the 25 same, drop by gravity and provide a support on which the shoulder or collar will rest during the removal of the engaged member from the well.

Having thus described my invention, what 30 I claim as new and desire to protect by Letters Patent is:—

1. A fishing tool for the described purpose, the same comprising a tubular support, a tubular shell carried thereby and formed 35 on its interior with a supporting shoulder, a trap ring within said shell and resting on said shoulder, and a plurality of upwardly swinging trap dogs pivotally mounted on said ring with their free edges overlying the 40 central openin~ of said ring.

2. A fishing tool for the described purpose, the same comprising a tubular support, a tubular shell carried thereby and formed on its interior with a supporting shoulder, 45 a trap ring within said shell and resting on said shoulder and a plurality of trap dogs carried by said trap ring and mounted to swing on a horizontal fulcrum said dogs being free to swing upwardly and precluded 50 from movement below a substantially horizontal position by contact with said trap ring.

3. A fishing tool for the described purpose, the same comprising a tubular support, 55 a tubular shell carried thereby, and a member removably positioned within said shell for engaging a member received within said shell, the same comprising a trap ring or base and a plurality of independent en-

gaging devices carried thereby and overlying the central opening of said trap ring. 60

4. A fishing tool for the described purpose, the same comprising a trap ring, a plurality of engaging members carried thereby and overlying the central opening 65 therein, a tubular shell within which said trap ring is removably positioned, means for supporting the ring within the shell, a tubular support for the shell, and means interposed between the support and ring for 70 maintaining the same on its support.

5. A fishing tool for the described purpose, the same comprising a trap ring, an 75 interiorly shouldered shell within which said trap ring is received and supported, 80 said ring being formed on its upper surface intermediate its opposite sides with an annular boss formed on its outer surface with an annular groove and provided at intervals with openings therethrough, a plurality 85 of trap dogs formed with arcuate faces overlying the opening of the ring and each provided with an apertured ear extending through the openings in said boss with their under-face resting on the body of 90 said ring adjacent to the inner wall of said boss, and a split ring positioned through said ear openings and receivable in said boss groove for retaining the trap dogs in position, and a tubular support to which said 95 shell is detachably secured.

6. A fishing tool for the described purpose, the same comprising a trap ring, a plurality 100 of pivotally mounted trap dogs carried thereby and overlying the opening 95 therein, said dogs when in their normal position providing an opening of a diameter smaller than that of the interior of said ring, an interiorly shouldered shell within which said ring is removably mounted and guiding 105 surfaces on the interior of said shell and ring for guiding the object over which said tool is lowered toward the opening formed by said dogs, and a support to which said shell is secured.

7. A fishing tool for the described purpose, the same comprising a tubular body, 110 a plurality of engaging members carried thereby and when in their normal position providing an opening in line with and of a diameter smaller than the interior opening of said tubular body, a tubular shell within which said body is removably mounted, and a support to which said tubular shell is 115 detachably secured.

In testimony whereof I have signed my name to this specification.

DENNIS L. DRISCOLL.
